Attn:

UNITED STATES PATENT OFFICE.

JOHN F. SLOAN, OF PEORIA, ILLINOIS.

THERMAL CUT-OUT CONSTRUCTION.

Application filed November 6, 1925. Serial No. 67,205.

My invention relates to a thermal cut-out construction.

One of the objects of my invention is to provide a fuse element for bridging between two contacts, which can be taken out after it is fused and replaced in reverse position to reestablish the circuit.

A further object of my invention is to provide a construction, as indicated above, which will be durable, cheap and effective.

Further objects will appear from the description and claims.

In the drawings in which my invention is shown—

15 Figure 1 is a side elevational view showing a thermal cut-out construction controlling the circuit through a heating element; and

Fig. 2 is an axial section through the fuse element.

20 Referring to the drawings in detail, the construction shown therein comprises a pair of contact clips 10 and 11 which are bridged by the fusible material 12 in the fuse element 13 and which may be connected in the 25 circuit of a heating coil housed in the container 14.

While the thermal cut-out construction is of general application, in the particular embodiment illustrated, the heating coil is located in a water jacket 14 which may be connected in the water cooling system of an automobile engine for which purpose it is provided with an inlet connection 15 at the bottom and an outlet connection 16 at the top.

30 The clips 10 and 11 may be of any usual suitable construction adapted to receive the cartridge type of fusible element.

The fuse element itself is reversible so that when the fusible material 12 is fused and runs from the position shown in Fig. 2 down the inclined tube to the dotted line position shown in Fig. 2 it breaks the electrical connection between the upper clip engaging contact 17 and the intermediate clip engaging contact 18 and bridges between the lower clip engaging contact 19 and the intermediate contact 18. This enables the connection between the clips 10 and 11 to be reestablished simply by removing the fuse element from the clip and reversing the fuse element end for end so that the contact 19 engages the upper clip 10 and the intermediate contact 18 engages the clip 11.

In the specific embodiment shown the container may be formed from two glass tubes 20 and 21 snugly seated within the flanges of the clips 17, 18 and 19. The inwardly extending annular bead 21 on the intermediate contact 18 provides a contact for intimate engagement with the fusible material 12. 55 60

In the particular construction shown, if the water jacket 14 becomes dry it causes a rise in the temperature of the casing 14 which soon melts the fusible material 12 and breaks the circuit through the heating coil. This saves current and prevents injury to the heating coil. The heating, of course, is not needed if the radiator and water circulation system is dry. When the water circulation system is again refilled the fuse element 13 can be withdrawn from the clips and reversed as outlined above to reestablish the circuit through the heating coil. 65 70

While I have shown but one embodiment of my invention, it is obvious that many modifications therein may occur to those skilled in the art and I desire, therefore, that my invention be limited only by the scope of the appended claim. 75

I claim:

80 A thermal cut-out construction comprising a pair of clips for embracing the annular contacts of a cartridge fuse, a reversible cartridge fuse comprising an insulating container having two annular end contacts and an intermediate contact, said annular end contacts being equally-spaced from the intermediate contact and said clips being spaced apart a distance equal to the distance between said intermediate contact and each of the end contacts, said annular end contacts being alternately engageable with one of said contact embracing clips, and said intermediate annular contact being engageable with the other contact embracing clip and a fusible element 85 in said container which when fused breaks electrical connection between the intermediate contact and one end contact and makes electrical connection between the intermediate contact and the other end contact. 90 95 100

In witness whereof I have hereunto subscribed my name.

JOHN F. SLOAN.
